UNITED STATES PATENT OFFICE.

ARATINE G. MOECKEL, OF DETROIT, MICHIGAN.

RAILWAY-SWITCH.

SPECIFICATION forming part of Letters Patent No. 655,449, dated August 7, 1900.

Application filed April 22, 1899. Serial No. 714,008. (No model.)

To all whom it may concern:

Be it known that I, ARATINE G. MOECKEL, a citizen of Germany, residing at Detroit, in the county of Wayne, State of Michigan, have 5 invented certain new and useful Improvements in Railway-Switches; and I do declare the following to be a full, clear, and exact description of the invention, such as will enable others skilled in the art to which it appertains 10 to make and use the same, reference being had to the accompanying drawings, and to the letters of reference marked thereon, which form a part of this specification.

This invention relates to switch mechanism 15 for railway-tracks; and it consists in the construction and arrangement of parts herein-after fully set forth, and pointed out particularly in the claims.

The object of the invention is to provide a 20 switch construction in which the arrangement is such as to allow for a free and unobstructed movement of the movable member of the switch and to provide against the clogging of said movable member by the accumulation 25 of dirt or snow and ice. This object is attained by the device illustrated in the accompanying drawings, in which—

Figure 1 is a plan view of my improved switch. Fig. 2 is a transverse section on line 30 2 2 of Fig. 1. Fig. 3 is a plan view of the switch, showing the movable member swung to a position opposite to that shown in Fig. 1. Fig. 4 is a longitudinal section as on line 4 4 of Fig. 3.

35 In illustrating this invention but one rail of the track is shown.

Referring to the letters of reference, A designates the rail of the main track, and B the rail of the intersecting track. These rails 40 are of the grooved pattern in common use.

C designates the bed-plate of the switch, which is let into the ground between the opposed ends of the rails of the track and is provided with a central concavity D, in which 45 is located the movable member of the switch. In the upper face of the bed-plate, on each side of the central concavity, is a depression a. Said depressions extend longitudinally of the plate and are provided with a flat bottom a. Said depressions extend longitudinally of the plate and are provided with a flat bottom 50 and a continuous outer inclined wall a'. Crossing the end portions of the bed-plate are

grooves b, which are adapted to register with the grooves in the intersecting rails. The movable member of the plate comprises a rectangular body portion E, adapted to lie within 55 the concavity D in the bed-plate and having a central integral tongue F, spaced from the walls of said plate, so as to form a way c on either side thereof for the flange of the wheels, which ways register with the grooves b in the 60 bed-plate.

The central movable member of the switch comprising the angle-plate E is pivoted at one end within the concavity in the bed-plate upon the vertical bolt e, the free end of said plate 65 being adapted to swing from side to side in said concavity upon said pivot. Projecting laterally from the vertical sides of the angle-plate E are the wings f, which are adapted to lie in the depressions a in the upper face of 70 the bed-plate and to form a closure over the central concavity D to prevent any obstructing object from falling into said concavity. These wings are equal in thickness to the depth of the depressions a, in which they lie, 75 so that the upper faces of said wings stand on a horizontal plane with the outer margins of said bed-plate. The marginal edges of said wings f throughout their entire length are beveled, as shown at i, forming a sharp 80 edge, which is adapted to cut under any accumulation of snow or ice which might form in the depressions a in the bed-plate and impede or arrest the movement of the member E of the switch. These beveled edges of said 85 wings entering under said obstructing formation loosen it and carry it upward out of said depression as the movable member of the switch is swung from side to side, the beveled outer edges a' of said depression allowing any accumulated matter loosened by 90 the wings f to be shoved out of said depression as said wings travel forth and back in their movement, thereby insuring at all times a free operation of the switch. 95

To guide the free end of the movable member of the switch in its swinging movement, a pin g (see Fig. 4) is employed, which projects downwardly from the under face of said member and engages in a slot in the bed-plate. (Shown by dotted line h in Fig. 2.) 100

With the parts in the position shown in

Fig. 1, a car traveling upon the rail A will move straight along said rail. Should it be desired, however, to switch the car onto the track B, the movable member of the switch 5 is swung so as to cause the tongue F to stand in the position shown in Fig. 3, when the flange of the wheel will be directed by said tongue onto the rail B, as is well understood. The movement of the swinging member of 10 the switch may be accomplished in any suitable manner.

Having thus fully set forth this invention, what is claimed is—

1. In a switch the combination of the bed-
15 plate having a central concavity therein, in-
tersecting rails joined to said plate, a mov-
able member pivoted within the concavity in
the bed-plate having two laterally-extending
flanges which project onto and at all times lie
20 upon the surface of said bed-plate to com-
pletely close said concavity, said movable
member having a centrally-disposed tongue
and a longitudinal channel on each side of
said tongue.
- 25 2. In a switch the combination of the bed-
plate having a central concavity, intersecting
rails joined to said plate, a movable switch
member pivoted within said concavity, a de-
pression in the upper face of said bed-plate
30 having a solid bottom and outwardly-beveled
walls, said movable switch member having a
centrally-disposed tongue with a channel on
each side thereof, said laterally-extending
wings lying in said depressions and closing the
35 concavity in the bed-plate, the edges of said
wings being provided with a continuous bevel

extending the entire length thereof, substan-
tially as set forth.

3. In a switch the combination of the inde-
pendent bed-plate, having a central concavity 40
and a horizontal surface extending laterally
from the opposite sides of said concavity, in-
tersecting rails detachably joined to said
plate, a movable switch member pivoted with-
in said concavity and carrying a section of a 45
rail, said movable member having lateral
flanges which project onto the horizontal sur-
face on each side of the concavity of said bed-
plate to close said concavity, said flanges hav-
ing continuous beveled edges, substantially 50
as set forth.

4. In a switch the combination of the bed-
plate having a central concavity and extend-
ing sides having a horizontal recess therein
leading from the edge of said concavity, a 55
movable member comprising a rectangular
body portion adapted to lie within the con-
cavity in the bed-plate and having a central
integral tongue spaced from the walls of the
body portion to form a way on each side of 60
said tongue, said body portion also having
horizontal wings projecting laterally from
the vertical sides of the angular body portion
and lying in the depressions in the upper face
of the bed-plate to all times close the con- 65
cavity therein.

In testimony whereof I sign this specifica-
tion in the presence of two witnesses.

ARATINE G. MOECKEL.
